GAME BOARD

David L. Stackhouse, Warwick, R. I.

Application January 31, 1951, Serial No. 14,054

Term of patent 14 years

(Cl. D34—5)

To all whom it may concern:

Be it known that I, David L. Stackhouse, a citizen of the United States, residing at Warwick, in the county of Kent and State of Rhode Island, have invented a new, original, and ornamental Design for a Game Board, of which the following is a specification, reference being had to the accompanying drawing, forming part thereof.

The single figure is a front elevation of a game board embodying my invention. The game board is of conventional thickness.

I claim:

The ornamental design for a game board, as shown and described.

DAVID L. STACKHOUSE.
